(57) **CLAIM**

The ornamental design for a case for mobile communication device, as shown and described.

DESCRIPTION

FIG. 1 is a top plan view of a case for mobile communication device showing our new design;

FIG. 2 is a front view of the case for mobile communication device of FIG. 1;

FIG. 3 is a right-side view of the case for mobile communication device of FIG. 1;

FIG. 4 is a rear view of the case for mobile communication device of FIG. 1;

FIG. 5 is a left-side view of the case for mobile communication device of FIG. 1;

FIG. 6 is a bottom plan view of the case for mobile communication device of FIG. 1;

FIG. 7 is a front isometric view of the case for mobile communication device of FIG. 1; and,

FIG. 8 is a rear isometric view of the case for mobile communication device of FIG. 1.
